UNITED STATES PATENT OFFICE.

WARREN G. JERNEGAN, OF CHESTER, SOUTH CAROLINA.

POST FENCE-FASTENER.

1,293,106.

Specification of Letters Patent.

Patented Feb. 4, 1919.

Application filed July 25, 1917. Serial No. 182,707.

To all whom it may concern:

Be it known that I, WARREN G. JERNEGAN, citizen of the United States, residing at Chester, in the county of Chester and

5 State of South Carolina, have invented certain new and useful Improvements in Post Fence-Fasteners, of which the following is a specification.

This invention relates to post fence-fas-10 teners and has for an object the provision of a fastener of this character which is sus-ceptible of attachment to fence-posts of vary-ing dimensions.

Another object is to provide a fastener 15 capable of securely retaining the fence wire in engagement therewith while at the same time permitting prompt disengagement of the wire therefrom, when such is desired; said fastener being formed of a single strip 20 of wire having post engaging sections and twisted at one end into a fence-wire retaining clip.

With the above and other objects in view, 25 the invention consists in the details of construction, arrangement and combination of parts as will be hereinafter more fully referred to in the following description, and pointed out in the accompanying drawings, wherein:—

30 Figure 1 is a perspective view of a fence post with the improved fasteners in place thereon,

Fig. 2 is a horizontal section taken 35 through the post, and;

Fig. 3 is an enlarged detail view of the 40 fastener as it appears prior to its attachment to a fence post.

Although the fastener is equally applica-45 ble to posts of other designs and shapes, for purpose of conveniently describing the fastener, the latter is illustrated in the present instance, as applied to a fence post 1 of rec-tangular shape, and provided with an en-50 larged base 2. The upper end 2 of the post is conical and flattened at its apex 4, while the corners 5 of the post are beveled throughout their length and shows to ad-vantage how the securing arms of the fastener adhere and conforms to the contour 55 of the post.

At appropriate places about the post are disposed the fasteners 6 which engage and retain the fence in close connection to the fence-posts and as contemplated by this in-55 vention these fence-fasteners or clips are built up from a single strand of wire, pref-

erably round and of a somewhat resilient nature. In forming the fastener, the wire strip is first bent intermediate its extremities until substantially U-shaped, after which 60 the arms 7 and 8 of the U are crossed and recrossed over each other at a suitable dis-tance from the head of the U as indicated at 9. From the twist or joint 9 the respec-tive ends 7 and 8 are projected oppositely 65 from each other in the same straight plane and laterally of the loop portion 10; being at right angles to the latter. The loop 10 is bent in a curve at an intermediate point so that its forward or arched portion 11 70 extends in substantially vertical, spaced proximity to the rear portion 12, forming in conjunction with the latter, a hook mem-ber adapted to receive and support upon the bights 13 thereof the fence wires 14. 75

To provide a pocket or seat for the fence wire, the hook portions 11 and 12 have out-wardly bulging lower portions 15 in which the wire is accommodated after its passage through the open end of the hook, and in 80 order to prevent any casual dislodgment of the fence wire from its seat the passage between the head of the loop and the joint 9 is restricted; this being accomplished by the bending of the upper ends of the loop 85 branches 11 into angles substantially salient, with the vertex 16 of each disposed in closely spaced proximity to the joint 9 and yieldable in an outward direction when nec-essary to engage the hook with a fence wire. 90 From the vertices 16 and 17 of the hook is extended to project away from and slightly above the joint 9 so as to provide a lip whereby the fence wire 14 may be the more readily engaged and led between the por-95 tions 11 and 12 of the hook until it comes to rest upon the bights 13 as previously de-scribed.

The fastener is attached to the fence post 1 by means of the end strips 7 and 8, which 100 encircle the post in opposite directions, as shown to advantage in Fig. 1 of the draw-ings, until their respective extremities 18 and 19 meet upon preferably, the rearmost face of the post. These extremities are then 105 interlocked by being looped or twisted about each other in such a manner as not only to join the strips 7 and 8 but to so tighten the entire fastener about the post that it will remain rigid and stationary wherever 110 placed on the post.

From the above description it may be seen

that the fastener herein provided is one which is most simple and economical in character, capable of being loosened for adjustment along the post without necessitating any removal of the fastener from the post although such removal may be instantly effected, whenever desired.

Having thus described the invention what I claim as new and desire to protect by Letters Patent is:

A post fence fastener, comprising a single strand of wire having an intermediate portion bent back upon itself to form a U-shaped hook and the free ends of the strand 15 twisted together at the rebent portion and

extended in opposite directions, the U-shaped loop being bent to form a fence wire engaging hook, a portion of the loop near the free end being bent inward to coöperate with the twisted part to prevent casual dis- 20 placement of the fence wire, and the free end of the loop flaring outwardly from the twisted part.

In testimony whereof I affix my signature in presence of two witnesses.

WARREN G. JERNEGAN.
